CLAIM

The ornamental design for physical exerciser with a monitor, as shown and described.

DESCRIPTION

FIG. 1 is a perspective view of a physical exerciser with a monitor showing our new design, wherein the side bars are shown in a disassembled position;

FIG. 2 is a front view of the physical exerciser with a monitor, wherein the side bars are in the assembled position; FIG. 3 is a rear view thereof, wherein the side bars are in the assembled position;

FIG. 4 is a left side elevational view thereof, wherein the side bars are in the assembled position;

FIG. 5 is a top plan view thereof, wherein the side bars are in the assembled position; and,

FIG. 6 is a perspective view thereof, wherein the side bars are in the assembled position.

The indicia shown in broken lines in the drawings form no part of the design to be patented.
